UNITED STATES PATENT OFFICE.

PERCY EUGENE CHASE, OF COEUR D'ALENE, IDAHO, ASSIGNOR OF ONE-HALF TO JAMES H. WOOD, OF COEUR D'ALENE, IDAHO.

BELT-STRETCHER.

No. 893,982.

Specification of Letters Patent.

Patented July 21, 1908.

Application filed December 9, 1907. Serial No. 405,793.

To all whom it may concern:

Be it known that I, PERCY EUGENE CHASE, a citizen of the United States, and a resident of Coeur d'Alene, in the county of Kootenai and State of Idaho, have invented a new and Improved Belt-Stretcher, of which the following is a full, clear, and exact description.

The object of the invention is to provide a new and improved belt stretcher for stretching a belt for re-lacing or other purposes, and which stretcher is simple and durable in construction, arranged for convenient attachment to the belt and for drawing the ends up evenly and securely locking the stretcher in the adjusted position, thus holding the belt in the stretched condition for lacing.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a plan view of the improvement as applied; Fig. 2 is an enlarged transverse section of the same on the line 2—2 of Fig. 1; Fig. 3 is an enlarged end view of part of one 30 of the clamps, and Fig. 4 is a side elevation of the same.

The belt A is clampingly engaged near its ends by clamps B and C, alike in construction, and connected with each other by rods 35 D, secured in the clamps C and slidably engaging the other clamp B. On this slideable clamp B are secured rods E, on which are fulcrumed levers F, each pivotally connected by links G, G' with grippers H, H', engaging 40 the corresponding rod D. The grippers H and H' are preferably in the form of disks having elongated apertures H², H³, through which pass the rod D, the walls of the apertures H², H³ being beveled, say in opposite 45 directions, as plainly indicated in dotted lines in Fig. 1, to cause the grippers H and H' to alternately engage and bite the rods D, on the operator imparting a swinging motion to the lever F. The links G and G' are provided 50 with lugs G³ adjacent to the grippers H and H', to hold the latter at right angles to the links when the latter are moved forward. Now when the several parts are in the position shown in Fig. 1, and a swinging motion is 55 given to the levers F on opposite sides of the

belt A, then the grippers H bite on the rods D, to move the clamps B and C towards each other, with a view to stretch the belt A, the other grippers H' during this movement sliding loosely on the rods D. When the lever F is given a return swinging movement then the grippers H' engage and bite the rods D, while the other grippers H loosely slide over the rods. Now from the foregoing it will be seen that the clamps B and C are drawn towards each other on each forward or return swinging movement given to the levers F, and the clamps B and C are held in the adjusted position by the corresponding grippers H or H'.

Each of the clamps B and C is preferably constructed as follows: Transversely - extending beams I and I' are arranged one on top of the other, to receive the belt A between the two, and on the lower beam I' 70 and at each end thereof is secured a removable bearing J, on which is fulcrumed a stirrup K, extending over the end of the top beam I, as indicated in Figs. 3 and 4. On the top of the stirrup K is fulcrumed a cam 75 lever L, bearing on a bearing plate N, held on top of the beam I, so that when the lever L is swung downward, the beams I and I' are drawn towards each other, to firmly clamp the belt A between the beams. When 80 it is desired to remove the device from the belt, it is only necessary to swing the levers L upward to allow of swinging the stirrups K out of engagement with the beam I, to disconnect the beams I and I', and thereby 85 allow removal of the beams from the belt. The cam levers L are self-locking when in a lowermost position as shown in Fig. 3.

The belt stretcher shown and described is very simple and durable in construction, can 90 be cheaply manufactured and readily placed in position on the belt or removed therefrom after the belt is stretched and the ends of the belt are laced together.

Having thus described my invention, I 100 claim as new and desire to secure by Letters Patent:

1. A belt stretcher comprising clamps for engaging the belt near the ends thereof, two rods connected with one clamp and on which the other clamp is slidably mounted, hand levers fulcrumed on the said slideable clamp, and gripping devices engaging the said rods and connected with the said hand levers.
2. A belt stretcher comprising clamps for 110

clampingly engaging the belt near the ends thereof, two rods held on one clamp and 5 slidingly engaging the other clamp, a pair of grippers engaging each rod, and a hand lever fulcrumed on the slideable clamp and connected with each pair of the said grippers.

3. A belt stretcher comprising clamps for clampingly engaging the belt near the ends thereof, rods on opposite edges of the belt 10 and connected with one of the clamps, the other clamp being slidably mounted on the said rods, a pair of grippers for each rod and arranged to alternately grip the same, and a manually-controlled hand lever for actuating the said grippers fulcrumed on the said 15 slideable clamp.

4. A belt stretcher comprising clamps for clampingly engaging the belt near the ends thereof, rods on opposite edges of the belt 20 and connected with one of the clamps, the other clamp being slidably mounted on the said rods, a pair of grippers for each rod and

each having an elongated aperture provided with beveled walls for engaging and gripping the rod, links pivotally connected with the 25 said grippers, and a hand lever fulcrumed on the said slideable clamp and pivotally connected with the said links.

5. A belt stretcher provided with a clamp for engagement with the belt, the clamp 30 comprising cross beams between which the belt is passed, stirrups fulcrumed at each end of one beam and adapted to swing over the end of the other beam, and a cam lever fulcrumed on each stirrup for pressing the 35 beams toward each other.

In testimony whereof I have signed my name to this specification in the presence of two subscribing witnesses.

PERCY EUGENE CHASE.
